UNITED STATES PATENT OFFICE.

LOUIS B. HASBROUCK, OF ELMIRA, NEW YORK, ASSIGNOR TO ECLIPSE TEXTILE SERVICES, INC., OF ELMIRA HEIGHTS, NEW YORK, A CORPORATION OF NEW YORK.

SLUB CATCHER AND YARN CLEANER.

Application filed October 30, 1923. Serial No. 671,745.

To all whom it may concern:

Be it known that I, LOUIS B. HASBROUCK, a citizen of the United States, residing at Elmira, in the county of Chemung and State of New York, have invented certain new and useful Improvements in Slub Catchers and Yarn Cleaners, fully described and represented in the following specification and the accompanying drawing, forming a part 10 of the same.

This invention relates to a slub catcher and yarn cleaner, and aims to provide a means for eliminating slubs or bunches from soft, long, fiber yarn, such as worsted yarn.

15 While the device which I have invented is particularly adapted for use in connection with worsted yarn, it may also be used in connection with other yarns and may serve to clean yarn as well as to eliminate slubs 20 therefrom.

A slub catcher of the type used on cotton yarns and consisting usually of a pair of transverse blades between which the yarn is drawn, is inoperative when applied to 25 worsted yarn. This arises from the fact that the fiber of worsted yarn is much softer and much longer than that of cotton yarn. It has been found that when a worsted yarn is drawn through an ordinary slub catcher, 30 the long fibers scraped from the yarn by the blades form a ring about the yarn in front of the blades which soon becomes reattached to the yarn, forming a bunch which is drawn against the blades and causes the 35 yarn to break. This action of worsted yarns in ordinary slub catchers is known as "balling up", and has precluded the use of such slub catchers in connection with worsted yarn. A further difficulty arises 40 from the fact that worsted yarns are frequently knotted, and that if the blades of the slub catcher are set closely enough together to break the yarn when a slub is drawn against them, the yarn is also broken 45 whenever a knot encounters the blades. This is a disadvantage, since it necessitates retying all the knots in the yarn.

I have discovered that if a worsted yarn is drawn through a hole or eye, one wall 50 of which consists of a flat surface along which the yarn is drawn, balling up of the yarn in front of the eye is eliminated, because the flat surface positively prevents any fibers which may be scraped from the 55 yarn from passing completely around the

yarn to form a ring. I have discovered also that if a worsted yarn is passed between a flat surface and the edges of a plurality of blades mounted so that they may be moved away from the flat surface, knots on 60 the yarn will pass through without breakage of the yarn, while the presence of a slub on the yarn will cause it to break.

By combining these two principles which I have discovered, I have produced what I 65 believe to be the first successful slub catching device for use with worsted yarn. The nature and advantages of the invention may best be understood by a detailed description of the specific device embodying the invention 70 which is shown in the accompanying drawings in which:—

Fig. 1 is a top view of the device, including a phantom view of the cover;

Fig. 2 is a side elevation of the device; 75

Fig. 3 is a transverse section on the line 3—3 of Fig. 1;

Fig. 4 is a fragmentary top view showing one of the blades;

Fig. 5 is a fragmentary side view sectioned on the line 5—5 of Fig. 3, and showing the action of one of the blades in breaking the yarn when a slub is drawn against it; and

Fig. 6 is an edge elevation of one of the 85 blades.

The device illustrated has a frame 10 comprising a flat vertical plate 11, front and rear end members 12 and 13 projecting inwardly from the plate 11, a side bar 14 adjustably secured to the end members, and a support 15 projecting outwardly from the plate 11. The support 15 may be provided with a clip 17 by means of which it may be attached to a bar 18. A yarn guide and 95 tension device 20 is attached to the front end member 12 and a rear guide 21 is attached to the rear end member 13. The front and rear end members 12 and 13 have recesses 22, 23 formed in their upper edges 100 immediately adjacent to the plate 11. When the device is in operation, a yarn A is drawn through the thread guide and tension device 20, through the recesses 22 and 23, and out under the rear guide 21. The yarn is thus 105 drawn along the flat inner surface 24 of the plate 11.

On the side bar 14 are mounted a plurality of transverse blades which cooperate with the surface 24 of the plate 11 to form 110

eyes through which the yarn is drawn. Three such blades 30, 30', 30² are shown in the drawings. As they are all alike, a description of one of them will suffice. The 5 blade 30 is held with its upper edge substantially perpendicular to the plate 11 by a support 32 formed integral with the blade, extending perpendicularly to the upper edge of the blade, and pivotally mounted 10 on a pin 33 projecting upward from the short arm 34 extending inwardly from the side bar 14. The blade 30 may be inclined downwardly and rearwardly as shown. The operating edge 35 of the blade 30, that is, 15 the edge which is opposed to the surface 24, is sharpened by grinding the rear surface of the blade at 36. In the operative edge 35 of the blade is a notch 37 which is of sufficient size to permit free passage of 20 the yarn with which the device is ordinarily used. This notch is located at the level of the bottoms of the recesses 22 and 23 and co-operates with the surface 24 of the plate 11 to form an eye through which 25 the yarn may be drawn. The upper portion of the operative edge 35 above the notch 37 is rounded off at 38 to facilitate threading of the device.

The operative edge 35 of the blade 30 is 30 urged toward the surface 24 of the plate 11, by means of a compression spring 40 surrounding a post 41 on the inner side of the bar 14, and reacting between the bar 14 and a collar 42 whose outer end is in engagement with the support 32. The support 32 contains a recess 43 surrounding a neck 44 on the post 41. Outward movement of the blade 30, i. e., movement of its 35 operative edge 35 away from the surface 24, is limited by engagement of the support 32 with a shoulder 45 on post 41, while inward movement of the blade under the pressure of the spring 40 is limited by a shoulder 57 on the post 41.

40 The device is adjustable so that it may be used with yarns of different sizes. For this purpose the outer portion 50 of the front end member 12 is inclined outwardly at a small angle to the surface 24 and the outer 45 portion 51 of the rear end member 13 is parallel to the portion 50, but is placed slightly nearer the plate 11. The bar 14 has at its front end a portion 52 which is bent outwardly so as to make the same angle with the bar as the portion 50 makes with the surface 24. At its rear end, the bar 14 has a portion 53 which is bent inwardly at the same angle to the bar as that at which the portion 52 is bent outward. The portions 52 and 53 of the bar 30 are attached to the portions 50 and 51 of the end members in such manner that the bar may be adjusted longitudinally. This may be accomplished by securing the bar by means 60 of screws 55, which pass through longitudi- 65 nal slots 56 in the end portions 52 and 53 of the bar. Adjustment of the bar 30 toward the rear of the device brings it nearer the plate 11, while adjustment of it toward the front of the device brings it 70 further from the frame 10. In all positions of the bar, however, it remains parallel to the plate 11 so that the edges of the blades are always at a uniform distance from the surface 24. 75

The device is provided with a removable cover 60 which may be secured to the bar 14 by means of a nut 61 engaging a depending flange 62 formed at the outer edge of the cover. The inner edge 64 of the cover 80 is spaced from the surface 24 of the plate 11, so as to provide a slot 65 extending between the recesses 22 and 23. 85

The operation of the device in removing slubs from worsted yarn is as follows:— 85

The device is first adjusted, by moving the side bar 14 forwardly or rearwardly, in accordance with the size of the yarn which is to be drawn through it. The adjustment is such that the operative edges 35 of the 90 blades 30, 30', 30² are normally spaced from the surface 24 by a distance less than the diameter of the yarn to be used. 95

The device is threaded by passing a yarn A through the yarn guide and tension device 20, dropping it into the recesses 22 and 23 and the slot 65, and drawing it under the rear guide 21. As soon as a pull is applied to the yarn it moves each of the blades 30, 30', 30² outwardly against the 100 tension of its spring 40 to such extent that the yarn is immediately drawn down into the notches 37 of all the blades. It is then continuously drawn forward, passing through the holes or eyes which are formed 105 by the notches 37 and the surface 24 of the plate 11. The surface 24 prevents any fiber which may be scraped from the yarn from passing around the yarn and forming rings. The inclination of the blades tends to direct 110 any such fiber downwardly so that it falls from the bottom of the device and does not interfere with the travel of the yarn. 115

When a knot B is drawn through the device it raises each blade slightly against the force of its spring 40 so that the knot may pass by the blades in succession without retarding the travel of the yarn or causing the yarn to break. 120

When a slub or bunch C on the yarn is drawn into the device, the yarn is broken, even though the diameter of the slub C be no greater than that of the knot B. This is due in part to the fact that the slubs C are soft and tend to bunch up in front of 125 a blade, causing the yarn to break, as indicated in Fig. 5. If a slub succeeds in raising the first blade 30 sufficiently to pass by it without breaking the yarn, the slub is torn as it passes between the sharp opera- 130

tive edge 35 of the blade and the surface 24, so that it is more ragged and of larger diameter when it encounters the second blade 30'. If it does not bunch up in front 5 of the second blade 30' so as to break the yarn, it is further torn and bulged by this blade, so that the yarn is broken when it encounters the third blade 30''. It is important, therefore, that a plurality of blades 10 be used. A greater number of blades than is shown in the drawings may be used, but I have found that with ordinary worsted yarn, the use of three blades insures the breakage of the yarn when a slub is drawn 15 into the device.

While the device is thus an effective means for eliminating slubs from worsted yarns, it may also be used to clean both cotton and worsted yarns. I wish it clearly 20 understood, therefore, that my invention is by no means limited to the particular use of the device which has been described nor to the particular form and arrangement of the parts illustrated.

25 Certain features of the device illustrated and described in this application form a part of the subject matter of my co-pending applications Serial No. 582,384, filed August 17, 1922, and Serial No. 671,746 filed October 30, 1923.

What I claim is:

1. A device of the class described, comprising means providing a flat surface along which a yarn is drawn, a plurality of blades 35 transverse to said flat surface and having edges opposed thereto, a mounting for each blade permitting its edge to move toward and away from said flat surface, and a separate spring arranged to urge each blade 40 toward the flat surface.

2. A device of the class described, comprising means providing a flat surface along which the yarn is drawn, a plurality of blades transverse to said flat surface and having edges opposed thereto, a mounting for each blade permitting its edge to move toward and away from said flat surface, means for limiting outward movement of the blades, and means tending to urge the 50 blades toward the flat surface.

3. A device of the class described, comprising means providing a flat surface along which a yarn is drawn, a plurality of blades transverse to said flat surface and having 55 edges opposed thereto, a mounting for each blade permitting its edge to move toward and away from said flat surface, means for limiting such movement of the blade in each direction, and means tending to urge the blades toward the flat surface.

4. A device of the class described, comprising means providing a flat surface along which a yarn is drawn, a plurality of blades transverse to said flat surface and having 65 edges opposed thereto, a mounting for each

blade permitting its edge to move toward and away from said flat surface, means for limiting such movement of the blade in each direction, a separate spring tending to urge each blade toward the flat surface, and means 70 for adjustably varying the distance between the mountings of the blades and the flat surface.

5. A device of the class described, comprising means providing a flat surface along 75 which a yarn is drawn, a plurality of blades transverse to said flat surface and having edges opposed thereto and aligned notches in said edges, a mounting for each blade permitting its edge to move toward and away 80 from said flat surface, means for limiting such movement of the blade in each direction, means tending to urge each blade toward the flat surface, and means for adjustably varying the distance between the 85 mountings of the blades and the flat surface.

6. A yarn cleaner for removing particles from a traveling yarn, comprising means providing a flat surface along which the 90 yarn is drawn, and a plurality of transverse blades having operative edges opposed to said flat surface and spaced therefrom by a distance less than the diameter of the yarn, said edges being provided with aligned notches partially surrounding the yarn. 95

7. A yarn cleaner for removing particles from a traveling yarn, comprising means providing a flat surface along which the 100 yarn is drawn, a plurality of transverse blades having operative edges opposed to said flat surface and spaced therefrom by a distance less than the diameter of the yarn, said edges being provided with aligned notches partially surrounding the yarn, and yieldable mountings for said blades permitting 105 them to move outwardly from the flat surface so that the yarn may be drawn into said notches in the threading of the device.

8. In a device of the class described, means providing an eye through which a yarn is 110 drawn, said eye having one wall consisting of a flat surface extending longitudinally of the yarn and in contact therewith.

9. A device of the class described, comprising means providing a flat surface along 115 which a yarn is drawn, and a transverse blade having an edge opposed to said flat surface and a notch in said edge cooperating with said surface to form an eye through which the yarn is drawn. 120

10. A slub catching device for use with a traveling yarn, comprising a plurality of transverse blades having edges positioned to operate on the yarn in series, a separate mounting for each blade permitting its edge to move away from the yarn in a direction substantially perpendicular to the line of travel of the yarn, and a separate spring for each blade tending to urge its edge toward the 125 yarn. 130

11. In a device of the class described, an adjustable frame, comprising a fixed side member, end members extending therefrom and having outer surfaces, each inclined at the same angle to said side member, but spaced at different distances therefrom, a movable side member having end portions inclined to it at the aforesaid angle, one of said end portions being inclined inwardly and the other outwardly, and means for securing the end portions of the movable side member against the outer surfaces of the end members while permitting longitudinal adjustment thereof to vary the distance between the fixed and movable side members. 10 15

In testimony whereof I have hereunto set my hand.

LOUIS B. HASBROUCK.
